COMBINED ROTATING CAFETERIA TYPE FOOD SERVICE COUNTER AND DISPLAY CASE

Elmer R. Weddendorf, Cincinnati, Ohio, assignor to
B/W Metals Company, Inc., Fairfield, Ohio

Filed Sept. 3, 1974, Ser. No. 503,028

Term of patent 14 years

Int. Cl. D6—04

U.S. Cl. D6—146

Fig. 3

Fig. 4

FIG. 1 is a front elevational view of a first embodiment of a combined rotating cafeteria type food service counter and display case showing my new design;

FIG. 2 is a top plan view of the first embodiment shown in FIG. 1 and the second embodiment shown in FIG. 5;

FIG. 3 is a rear elevational view of the first embodiment shown in FIG. 1;

FIG. 4 is a cross-sectional top plan view of the first embodiment shown in FIG. 1 taken along line 4—4 of FIG. 1 showing the rotating counter surface adapted for buffet style service;

FIG. 5 is a front elevational view of a second embodiment of a combined rotating cafeteria type food service counter and display case showing my new design;

FIG. 6 is a rear elevational view of the second embodiment shown in FIG. 1; and

FIG. 7 is a cross-sectional top plan view of the second embodiment shown in FIG. 5 taken along line 7—7 of FIG. 5 showing the counter surface adapted for pre-dished food style service.

I claim:

The ornamental design for a combined rotating cafeteria type food service counter and display case, substantially as shown and described.
